PACKAGE FILLING DEVICE CONNECTED TO
A CONVEYER MOUNTED IN A CHANNELLED
GUIDE

Alvin Bernard Filbert, Baltimore, Md.

Application December 23, 1947, Serial No. 793,425

2 Claims. (Cl. 226—58)

1

This invention relates to a package filling device and while not intended to be specifically limited thereto is more especially intended for and useful in connection with the filling of bags or the like with oleomargarine.

An object of the invention is to provide a means for supporting and maintaining a bag or the like with the mouth thereof distended for reception of a filling portion of the intended contents of the bag.

A further object is to provide a means in the form of an annulus and having a support therefor mounted on a conveyor to be thereby automatically brought into operative relation to a filling spout for filling a bag or like container distendably supported by said annulus.

A further object is to provide a device in the form of a support having mounted thereon a means for holding open the mouth of a bag or like container, and with said means either in the form of a continuous ring or a split ring but not necessarily circular in shape as the invention is applicable to circular, irregular, rectangular or other shapes.

Heretofore, in the packaging of oleomargarine and similar products, but especially oleomargarine, the product was molded or handled similarly to the manner of handling and packaging of butter. At the present time there are available containers in the form of bags, made of plastic substances which are odorless and which can be sealed so as to permit the contents to be "worked" or kneaded in the bag. For example, in the case of oleomargarine, the coloring capsule can be inserted and when the bag is sealed, the capsule can then be broken and its contents dispersed throughout the oleomargarine by kneading or working the contents in the sealed bag. With the present invention, these bags can be mounted very rapidly by an operator and the bags filled with the product in a fluent state, after which the bags can be sealed, then the contents hardened and packaged in outer wrappers.

To the foregoing objects and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a fragmentary top plan of a conveyor having a bag supporting means secured

2

thereto constructed according to an embodiment of this invention.

Figure 2 is a fragmentary sectional view taken substantially on the line 2—2 of Figure 3.

Figure 3 is a sectional view taken on the line 3—3 of Figure 1.

Figure 4 is a fragmentary side elevation, partly in section, of the base or lower portion of the device.

Figure 5 is a plan view of the bag supporting means removed from the base.

Figure 6 is a plan view of a modified form of bag supporting means.

Figure 7 is a plan view of another modified form of bag supporting means.

Figure 8 is a plan view of a further modified form of bag supporting means.

Referring to the drawings, the numeral 10 designates generally a conveyor which in the present instance is in the form of a chain conveyor and the chain is constructed in the form of a plurality of pivotally connected together plates 11 having spiral loops 12 at each end thereof for pivotal engagement with spiral loops 13 of adjacent plates 14. The chain 10 is adapted to travel in the confronting channels of a pair of channel members 15 which include lower horizontal sides 16, vertical webs 17 and upper horizontal sides 18. In the filling of bags such as bags or containers for receiving oleomargarine or other material the bags B are adapted to be supported in an upright open position so that the liquid material may be discharged into the open mouth of the bag B from a discharge nozzle 19. The conveyor 10 may be either continuously or intermittently operated so that the material from the nozzle 19 may be discharged in a predetermined quantity within the bag B.

The bag B is adapted to rest at its lower end 40 on a plate 20 which is secured to the chain 10 by means of a pair of downwardly extending clamping arms or fingers 21. The clamping arms or fingers 21 are adapted to engage on diametrically opposite sides of the convolutions of 45 the coils 12 and 13 formed between the chain links and the arms 21 are adapted to loosely engage between the confronting channel members 15 with the plate 20 slidingly engaging on the upper sides 18 of the channel members 15. The bag B is held in open position by means of an annulus or ring 22 which engages within the upper end of the bag B and the ring 22 is supported above the plate 20 by means of an elongated bar 23 which is threaded as at 24 at its 50 lower end into the plate 20. The upper end of

the supporting bar 23 is reverted as indicated at 25 and the reverted end 25 is then welded, soldered or otherwise firmly secured as at 26 to the bag distending ring 22.

Referring now to Figure 6, there is disclosed a modified form of bag supporting and distending means wherein the ring 27 is split as indicated at 28 so that the ring 27 may be made slightly larger than the inside dimension of the bag B and when inserted within the mouth of the bag will frictionally hold the bag in upright position.

Referring now to Figure 7, there is disclosed another form of bag distending means which includes a rectangular ring or member 29. The rectangular member 29 in the present instance is formed as a square but it will be understood that this rectangular member 29 may be of any polygonal configuration.

Referring now to Figure 8, there is disclosed a further modification of bag distending means which includes a split polygonal ring or member 30.

In the use and operation of this invention the bag B is inserted about the supporting ring or annulus 22 preferably by initially holding the bag in the horizontal position so as to dispose the distending member 22 endwise within the open end of the bag. The bag is then swung downwardly through an arc of substantially 90° with the upper end of the bag extending slightly above the ring or annulus 22 as shown in dot and dash lines in Figure 3. With a bag supporting means as hereinbefore described the empty bags are firmly supported in an upright position so that the liquid or other material may be discharged into the bag and after the bags have been filled by discharge of material from the discharge nozzle 19 the bags may be readily removed from the supporting member 22 and the

conveyor, that is, the distending member 22 is initially inserted into the open end of the bag by disposing the flat bag so that it lies in the plane of the distending member.

5 I claim:

1. In a bag filling machine having a horizontally movable conveyor and a channelled guide for the conveyor; means for supporting a bag in upright position comprising a bottom plate 10 slidable on said guide, means securing said plate to said conveyor, a bag distending member, and means supporting said bag distending member above and from said plate.

2. In a bag filling machine having a horizontally movable conveyor and a channelled guide for the conveyor; means for supporting a bag in upright position comprising a bottom plate 15 slidable on said guide, depending fingers on said plate extending into said channelled guide and 20 engaging said conveyor for moving said plate with said conveyor, an upstanding supporting bar carried by said plate adjacent the edge thereof, and a bag distending member secured to the upper end of said bar and disposed above said 25 plate.

ALVIN BERNARD FILBERT.
